UNITED STATES PATENT OFFICE.

JAMES C. BLAIR, OF TOLEDO, OHIO, ASSIGNOR TO THE LIBBEY-OWENS SHEET GLASS COMPANY, OF TOLEDO, OHIO, A CORPORATION OF OHIO.

SHEET-GLASS APPARATUS.

Application filed June 24, 1926. Serial No. 118,159.

The present invention relates to sheet glass apparatus.

An important object of the invention is to provide a process and an apparatus for producing sheet glass of a uniform and substantially predetermined thickness.

Another object of the invention is to provide an apparatus wherein a sheet is flowed on a slab and including means for reducing 10 the sheet, after it leaves or as it leaves the slab, to a substantially predetermined thickness.

A further object of the invention is to provide a sheet glass apparatus wherein 15 molten glass, flowing from a receptacle under the head pressure of the glass in said receptacle, is passed down a slab in sheet form, the sheet having a thickness substantially greater than the desired thickness of 20 finished sheet, the apparatus including means for reducing the said sheet to the proper thickness.

A still further object of the invention is to provide an apparatus wherein a sheet is 25 flowed down an inclined slab under the head pressure of its source, the apparatus including a pair of rolls arranged at the end of the slab, creating a sheet forming pass through which the sheet from the slab passes 30 to be reduced to a predetermined thickness.

Still another object of the invention is to provide an apparatus wherein a sheet is 35 flowed down an inclined slab under the head pressure of its source, the apparatus including a pair of rolls arranged at the end of the slab, creating a sheet forming pass through which the sheet from the slab passes to be reduced to a predetermined thickness, a straight line through the axes of the rolls 40 being substantially at right angles to the plane of said slab.

The drawing shows a fragmentary vertical longitudinal section through my improved machine. In the drawing the 45 numeral 5 designates a receptacle adapted to be continuously supplied with a source of molten glass 6. Arranged below the surface 7 of the glass is an adjustable slab 8, preferably formed from a non-corrosive metal such as nichrome, Monel, stellite, etc., although of course the slab may be formed from cast iron or the like. The slab 8 is 50 provided with temperature control means

such as the burner 9. Arranged above the slab, preferably at the end thereof nearest 55 the receptacle 5, is an adjustable gate 10, preferably formed from a heat resisting non-corrosive metal, and being provided with an internal chamber capable of being heated by means of the burner or the like 60 11. The gate 10 is adjustably mounted and is adapted to control the quantity of glass permitted to flow from the receptacle 5. It will be seen that the slab 8 and the lower edge of the gate 10 forms a slot or opening 65 through which a stream of glass 12 flows under the head pressure of the molten mass 6. A sheet of substantial thickness 13 is thus permitted to flow down the slab 8. Arranged at the end of the slab 8 is a pair 70 of positively driven rotatable rolls 14 adapted to form a sheet forming pass through which the sheet or body of glass 13 passes to reduce the same to a sheet 15 of substantially uniform and predetermined thickness. 75 The sheet 15 is then passed through an annealing leir 16 to gradually reduce it to room temperatures, being supported in the leir by means of conveyor rolls 17.

A cooler 18 is provided at the juncture 80 of the receptacle 5 and the slab 8 to freeze what little glass tends to leak therebetween. The rolls 14 are mounted in a suitable frame 19 in a manner that the space between the two rolls may be varied to permit the 85 formation of different thicknesses of sheets of glass. The rolls are positively driven through means of the gear arrangement 20, while the adjustment between the rolls is controlled by the means 21. The rolls and 90 slab are mounted in a suitable bracket 22, supported on a base 23 adjustable vertically by means of the jack screws 24.

The sheet of glass produced by this construction is relatively very flat and of a pre- 95 determined thickness, and is therefore particularly well adapted for use as a plate glass blank. An adjustable shear cake 25 may be placed in the molten glass 6 to skim the glass before it is flowed through the 100 opening between the gate 10 and slab 8.

It is to be understood that the form of the invention herewith shown and described is to be taken as the preferred embodiment of the same, and that various changes in the 105 shape, size and arrangement of parts may

be resorted to without departing from the spirit of the invention or the scope of the subjoined claims.

Claims:

5. 1. In sheet glass apparatus, a receptacle containing a mass of molten glass, a slab associated with the receptacle, means for flowing a relatively thick sheet of glass down the slab, and a pair of rolls arranged at the 10 end of the slab for reducing the sheet in thickness, and means for moving the slab and rolls simultaneously.
15. 2. In sheet glass apparatus, a receptacle containing a mass of molten glass, a slab associated with said receptacle for receiving the molten glass therefrom, an adjustable gate for controlling the amount of glass flowing onto the slab, means for internally heating said gate, and means for reducing the 20 glass to a substantially predetermined thickness as it leaves the slab.
25. 3. In sheet glass apparatus, a receptacle containing a mass of molten glass, a slab associated with said receptacle for receiving the molten glass therefrom, an adjustable gate for controlling the amount of glass flowing onto the slab, means for internally heating said gate, means for reducing the glass to a substantially predetermined thickness 30 as it leaves the slab, and means for adjusting the slab and rolls simultaneously.
35. 4. In sheet glass apparatus, a receptacle containing a mass of molten glass, a slab for receiving the molten glass therefrom, an adjustable gate associated with said slab to form a glass outlet, heating means for creat- 40 ing a flame within said gate and directing it toward said outlet, and means for reducing the glass to a substantially predetermined thickness as it leaves the slab. 45
5. In sheet glass apparatus, a receptacle containing a mass of molten glass, a slab for receiving the molten glass therefrom, an adjustable gate associated with said slab to form a glass outlet, heating means for creat- 50 ing a flame within said gate and directing it toward said outlet, means for reducing the glass to a substantially predetermined thickness as it leaves the slab, and means for moving the slab and rolls simultaneously. 55
6. In sheet glass apparatus, a receptacle containing a mass of molten glass, a slab associated with said receptacle, means for flowing a sheet of glass down the slab, a pair of rolls for reducing the thickness of said sheet as it leaves the end of the slab, a bracket carrying both the slab and rolls, and means for adjusting the bracket to move the slab and rolls simultaneously. 60
7. In sheet glass apparatus, a receptacle containing a mass of molten glass, an inclined slab associated with the receptacle, means for flowing a sheet of glass down the slab, a pair of rolls arranged at the end of the slab for reducing the sheet to substantially a predetermined thickness, means for simultaneously adjusting said slab and rolls, and means for adjusting said rolls only. 65

Signed at Toledo, in the county of Lucas, and State of Ohio, this 21st day of June, 70 1926.

JAMES C. BLAIR
